UNITED STATES PATENT OFFICE.

HARRY A. CUMFER, OF CHICAGO, ILLINOIS, ASSIGNOR OF ONE-HALF TO ALBERT D. STEWART, OF HUTCHINSON, KANSAS.

PLASTER-RECEIVING BOARD.

Original application filed August 17, 1922, Serial No. 582,344. Divided and this application filed April 3, 1926. Serial No. 99,498.

This invention relates to plaster-receiving board, and is a division of an earlier application filed by me under date of August 17th, 1922, Serial No. 582,344.

5 One of the objects of the invention is to improve the construction of plaster-receiving boards of the type made of two associated sheets, of which one is imperforate, by providing a structure that may conveniently be made by a machine from a constantly moving strip or sheet of suitable material.

10 Another object is to provide improved means for securing the sheets together and 15 to the supporting wall.

Another object is to provide pockets for 20 plaster between the two sheets by pressing parts of one or both sheets out of normal planes and cementing the displaced parts to the inner surface of the other sheet within the pockets or channels.

25 Another object is to provide a structure, of the class described, in which alternate channels are not so wide as the intermediate, 30 plaster-containing channels.

Another object is to provide a plaster-receiving structure made of two united sheets, the outer sheet having perforate channels to receive plaster, the inner sheet 35 having an inclosed imperforate channel, like walls of the channels being cemented together.

Other objects and advantages of the invention will hereinafter appear from a consideration of the following description, 40 when taken in conjunction with the drawings, wherein:—

Fig. 1 is a cross sectional view taken on line 1—1 of Fig. 2.

45 Fig. 2 is a plan view of Fig. 1 with certain parts in section.

Fig. 3 is a section taken on line 3—3 of Fig. 4 showing a variation of my invention.

Fig. 4 is a reduced plan view of Fig. 3.

50 Fig. 5 is a similar view of a similar structure.

In all the views the same reference characters may be employed to indicate similar parts.

55 The structure is made of two sheets of suitable material having composite pockets to receive plaster that may be applied to its outer surface, provided by displacement of portions of either sheet, the displaced por-

tions of one sheet being cemented or otherwise secured to the other sheet. 55

In every instance the outer sheet is perforated to permit the plaster to enter the pockets or channels between the sheets and the inner or base sheet is imperforate to 60 make the structure wind and water proof.

A suitable substance of which to make the structure is composition roofing made of a fibrous base 5 of felt, or the like, saturated with a water-resistant such as asphaltum or 65 a compound thereof and coated on both sides with a similar material 6, more or less plastic when warm and which forms a strong cement when cold. The lower or base sheet 7 is imperforate. The upper or outer sheet 70 8 is formed into channels 9 and 10. The alternate channels 9 may be wider than the intermediate channels 10.

The smaller channels are utilized to nail 75 both sheets to the supporting wall 11.

Contacting portions of the two sheets are cemented together at 13.

In Figs. 1 and 2 the outer sheet 8 is slotted longitudinally at intervals to provide plaster receiving openings and the tongues 12^a are 80 bent inwardly and cemented to the upper surface of the sheet 7. In Figs. 3 and 4 the slits are made so as to divide the tongues to provide portions 20 which are parallel with the base sheet and cemented thereto. This 85 affords a larger surface contact than the form shown in Fig. 1. The parts 12^a form strengthening projections extending from one sheet and cemented to the other sheet within the plaster-receiving channels 9. 90

Nails 18 are driven through both sheets 7 and 8 within the narrow channels and into the support 11. Cementing the parts 12^a to the opposite sheet prevents the walls of the channels 9 from sagging when the board is 95 nailed to a ceiling. Either one of the forms of the board may conveniently be made by a suitable machine from constantly moving sheets of material of which it is to be made.

The contacting surfaces of the sheets may be held together while the asphaltum is hot and, while so held, a cooling agent such as water or the like may be applied before they are released, whereupon the surfaces will be 100 firmly held together by the relatively cold 105 plastic.

In Fig. 4 the slits 21 divide the projections into two parallel tongues each equal

to the entire width of the opening made by their displacement from the bottom sheet, while the slit 22 Fig. 5 produces two tongues, each about one-half the length of the opening. The openings are made in the outer wall of the closed channel in each case and through these openings plaster will pass into the interior of the channels 9.

I claim as my invention:

- 10 1. A plaster receiving board comprising a base sheet and an overlying sheet having alternate inwardly and outwardly extending self-supporting channels substantially rectangular in shape, the crest of the inwardly extending channel being perforated to provide plaster keying means, the incised portions formed by the perforations being depended downwardly and affixed to the base sheet.
- 15 2. Corrugated board comprising two sheets, one sheet formed into a series of alternate channels and ridges, having surfaces parallel to the other sheet, said channels fixedly attached to the other sheet, the ridges having incisions therein, through which a plastic substance applied to the sheet keys is fixed thereto, parts of the incised portions being attached to the other sheet.
- 20 25

3. A corrugated board comprising two sheets, a base sheet and an overlying sheet, the latter formed into a series of alternate channels and ridges, the channels fixedly united to the base sheet, the ridges having incisions therein adapted to produce apertures through which to key a plastic substance applied thereto, free portions produced by said incisions depressed and fixedly adhering to the base sheet.

4. Corrugated board including a base sheet and an overlying sheet, the latter formed into a series of alternate channels and ridges, portions of said channels being fixedly attached to the other sheet, the ridges having incisions therein, free portions produced by said incisions being firmly attached to the surface of the other sheet.

5. Corrugated board including a base sheet and an overlying sheet, the latter formed into a series of alternate channels and ridges, said channels fixedly attached to the other sheet, the ridges having incisions therein, through which a plastic substance applied to the sheet may be keyed, free portions produced by said incisions being firmly attached to the surface of the other sheet.

HARRY A. CUMFER.
